UNITED STATES PATENT OFFICE.

JOHN H. PARMELEE, OF BRIDGEPORT, CONNECTICUT, ASSIGNOR OF ONE-HALF TO FRIEND W. SMITH, OF SAME PLACE.

DESIGN FOR A TOY MONEY-BOX.

SPECIFICATION forming part of Design No. 12,316, dated June 14, 1881.

Application filed March 22, 1881. Term of patent 7 years.

To all whom it may concern:

Be it known that I, JOHN H. PARMELEE, of Bridgeport, Fairfield county, Connecticut, have invented and produced a new and original Design for Toy Money - Banks, of which the following is specification.

My invention consists of a design for toy money-boxes in which there appears a representation of two faces exhibiting opposite emotions of joy and sorrow or satisfaction and disappointment. This effect may be produced by casting, painting, or in any other manner embellishing the material (preferably metal) composing the box.

15 The drawing is a perspective view, showing a face of joy as properly presented to view, while the reversed face indicates an expression of sorrow or disappointment.

I have shown the heads covered by hats, 20 around the bands of which may be painted, printed, or otherwise formed, any motto, letters, or precepts, to give additional character to the facial expressions. In the crown of one or both of the hats an ordinary slot for the

introduction of money appears, and the said 25 crowns are in horizontal planes to serve as bases for the box to rest upon. The general arrangement of the design is such as shown, so that different expressions of countenance may be presented to view as the box is caused 30 to rest upon one or the other of its bases.

I do not wish to confine myself to any particular expressions in the countenance, as they may be varied considerably without departing from the general characteristics of the design, 35 the essential feature of which is the presentation of two faces having different expressions.

What I claim is—

The design for toy money - boxes herein shown and described, the same consisting of 40 two faces of different expressions.

Witness my hand and seal this 5th day of February, A. D. 1881.

JOHN H. PARMELEE. [L. S.]
